UNITED STATES PATENT OFFICE.

LEON EMMANUEL BRUNO DESMARQUOY, OF PARIS, FRANCE.

RESILIENT PADDING.

Application filed April 4, 1925, Serial No. 20,770, and in France November 21, 1924.

For the various padding utilized in coach-building as well as for airplanes and domestic purposes, horse hair, palm fibre and felt are commonly used.

5 Besides their high cost price these materials also have the disadvantage of being injured by moisture.

Furthermore, the said fibrous materials have no resiliency of their own, and therefore do not permit resilient paddings to be obtained; moreover they are liable to sag in some parts of the quilting or upholstering and to pile up in other parts so that hitherto known paddings offer, after a comparatively 10 short use, parts more or less unstuffed and parts compact and hard.

Despite their utter lack of resiliency and multiple drawbacks, such stuffings are commonly used, in airplane building, for instance, to pad the gunwale of the car or cockpit in order to protect from shock the pilot's or passenger's head.

They can also be used for padding cells in lunatic asylums.

25 In their practical uses as shock-protectors or absorbers hitherto known stuffings are admittedly in adequate, and, especially in the two cases above mentioned as examples, numerous preventable accidents, some of them 30 fatal, have been officially ascertained to have resulted from such defective padding.

The object of my invention is to provide a novel cushioning or padding material designed to do away with the above stated 35 objectionable features and which, while applicable to paddings in general, is essentially characterized by the fact that it consists of small particles of spongy rubber waste enclosed in a canvas or other fabric wrapper 40 made of the form suitable for the proposed padding and which may or may not be contained in an outer envelope of flexible material, as leather, kid or parchment, for instance special devices being devised for fixing the stuffing on the part to be padded.

In order to make my invention more clearly understood, I have illustrated an embodiment thereof, as applied to the cockpit of an airplane, in and by the drawing appended hereto and wherein:

Figure 1 is a diagrammatic cross sectional view of the improved padding and Figure 2 a plan view showing the padding in place on the gunwale of an airplane.

55 Figure 3 is a perspective view of the pad-

ding, Figure 4 a side elevation thereof, and Figure 5 an end view of Figure 3.

In all the figures the same numerals denote the same parts.

As shown by the drawing, the stuffing 60 which is the subject matter of my invention is essentially constituted of spongy-rubber waste cut into bits about 1 to 2 centimeters in size. Said stuffing is enclosed in a canvas envelope 2 inside which it is maintained by 65 machine- or hand-made seams which may be arranged in any suitable manner according to the form that the packing is to have.

In the embodiment shown I have formed by means of the canvas covering 2 a main 70 member or body 1 and two other members or arms 3 and 4, integral with the aforesaid body member 1 (which they prevent from turning), and kept in shape, on the one hand by stitching 5 or by any other means, and 75 on the other hand, by flaps 6 made with the canvas on the edge of the said padding. The whole is covered with a flexible envelope 7, made of parchment, leather or any other similar material, the edges 9 of which are 80 folded over and cover the said flaps 6.

On the flaps 6 are suitably spaced and secured at intervals eyelets 8 which fasten the leather or parchment part 7 to the flaps 6. The padding so constituted is fitted on 85 the part to be covered by engaging the latter in the central space or gutter of the padding and closing the flaps 6, then threading a wire or thread through the eyelets 8 and through holes previously pierced through 90 the part to be padded, so as to register therewith. Any other suitable method of securing, may, of course, be substituted for this lacing.

Moreover the above application is described merely as an example and the padding may be given according to its intended purpose various forms widely different from the one shown.

Whatever its exterior form the padding 100 which is the subject matter of my invention is constituted, as already explained, by small bits of spongy rubber contained in a stitched canvas envelope forming a compact quilt which, owing to the special nature of spongy 105 rubber, is very light and excessively resilient.

The padding obtained according to my invention is practically imputrescible, so that the resiliency of such padding remains constant and it can therefore be efficiently used 110

as a shock-absorbing or damping lining or armor.

Such padding is furthermore insulating and far more comfortable than the present horsehair paddings and offers also, as compared with these, the important advantage of a much inferior cost-price.

Obviously, applications of the filling material covered by my invention are numerous, since such material can be used not only in constructing the hereinbefore described paddings but also in making resilient pads, cushions, etc.

Having now particularly ascertained and

described the nature of my said invention as well as the manner in which the same is to be performed, I declare that what I claim is:

Resilient cushion padding, comprising a filling, a wrapper enclosing the same; said wrapper and its filling being shaped to form a member of trough- or U-section, the opposite arms of which are provided at their inner ends with stitching and at their free outer edges with flaps; and a flexible outer envelope enclosing said wrapper and having its edges folded over said flaps.

In testimony whereof I affix my signature.
LEON EMMANUEL BRUNO DESMARQUOY.
